DESIGN.

E. T. CURRAN.

COMBINED RADIATOR CAP AND TEMPERATURE INDICATOR.

APPLICATION FILED SEPT. 29, 1920.

60,749.

Patented Apr. 4, 1922.

Inventor:

E. T. Curran,
By his Attorney *John O. Seifert*

UNITED STATES PATENT OFFICE.

EDWARD T. CURRAN, OF DETROIT, MICHIGAN.

DESIGN FOR A COMBINED RADIATOR CAP AND TEMPERATURE INDICATOR.

60,749.

Specification for Design.

Patented Apr. 4, 1922.

Application filed September 29, 1920. Serial No. 413,625. Term of patent 7 years.

To all whom it may concern:

Be it known that I, EDWARD T. CURRAN, a citizen of the United States, residing in the city of Detroit, in the county of Wayne and State of Michigan, have invented a new, original, and ornamental Design for a Combined Radiator Cap and Temperature Indicator, of which the following is a specification, reference being had to the accompany-

ing drawing, forming a part thereof, in which the figure is a front elevation showing the design.

I claim:

The ornamental design for a combined radiator cap and temperature indicator as shown.

EDWARD T. CURRAN.
